(No Model.)

W. W. MCKAY.
HITCHING ANCHOR.

No. 425,385.

Patented Apr. 8, 1890.

UNITED STATES PATENT OFFICE.

WILLIAM W. MCKAY, OF STANTON, (DAKOTA TERRITORY,) NORTH DAKOTA.

HITCHING-ANCHOR.

SPECIFICATION forming part of Letters Patent No. 425,385, dated April 8, 1890.

Application filed September 10, 1889. Serial No. 323,522. (No model.)

To all whom it may concern:

Be it known that I, WILLIAM W. MCKAY, a citizen of the United States, residing at Stanton, in the county of Mercer and Territory 5 of Dakota, have invented certain new and useful Improvements in Hitching-Anchors; and I do declare the following to be a full, clear, and exact description of the invention, such as will enable others skilled in the art to which it app. 10 pertains to make and use the same, reference being had to the accompanying drawings, and to the letters of reference marked thereon, which form a part of this specification.

My invention, which is in the nature of an 15 anchoring-pin adapted to be driven into the ground at any desired point in the field or other place to afford a convenient means for hitching horses, cows, &c., thereto has for its object to provide a simple, cheap, and strong 20 device of this character which may be quickly anchored at any desired place and which may be readily and quickly withdrawn from the ground when it is desired to place it at some other point or carry same away.

25 To this end my invention consists in certain novel features of construction and peculiar combination of parts, all of which will be hereinafter fully described in the annexed specification and particularly pointed out in the claims.

30 In the accompanying drawings, Figure 1 is a side view of my improvement, showing same in operative position in the ground. Fig. 2 is a detail perspective view of the collar or 35 guide-piece. Figs. 3, 4, and 5 are detail views hereinafter specifically referred to, and Fig. 6 is a view of a modification of the collar or guide-piece.

In carrying out my invention I employ a 40 circular band or collar A, which I provide in its upper part with apertures $a' a'$, arranged one to each side of the center of the collar, and a transverse elongated slot a disposed in the lower part thereof and centrally between the apertures $a' a'$.

45 B B denote the anchoring bolts or pins, each provided with a suitable head $b b$, the shank portions of which are inserted through the apertures $a' a'$ and the central slot a , said 50 slot being of a size sufficient to conveniently allow both shanks to pass therethrough. By

this arrangement it will be observed that the pins B B are arranged to cross each other diagonally and that as the pins are withdrawn from the collar A they will pull in a direct 55 diagonal line and always maintain the same relation to each other.

C denotes a ring or loop held in the collar A, to which is secured one end of the animal-holding rope or chain D, as shown. After the 60 pins B B are first inserted through the collar A, as described, the lower ends thereof are pointed by hammering the ends and spreading the same, as at $b' b'$, this being done for the double purpose of providing the pins with 65 pointed ends and providing the same with enlarged flattened ends, which, while allowing the pins to be pulled up through the slot a , will not allow the pins to be withdrawn from the collar through the apertures $a' a'$. 70 By reference to Fig. 5 of the drawings it will be seen that by this construction the pins may, by turning the collar upside down, be dropped into parallel positions, into a compact form for shipping. 75

The manner of placing my improved hitching anchor or pin in the ground will be clearly understood by reference to Figs. 3 and 4 of the drawings. The collar or guide A is held to the ground with the pins drawn up, as 80 shown in Fig. 3. One of the pins B is then driven home, as shown in full lines, Fig. 4, and then the opposite pin is driven in, as shown by dotted lines in the same figure. Said pins being driven diagonally into the ground 85 serve to hold the collar securely in place. When it is desired to remove the device, by giving one or two sharp jerks on the rope D the pins will be slightly raised and may each then be readily withdrawn. 90

In Fig. 6 I have shown the collar provided with two apertures $a^2 a^3$ in the bottom thereof instead of a single slot a . By this arrangement the pins, which in this instance will not be provided with flattened ends but with tapering points, are diagonally passed through their respective pair of apertures $a' a^2$, and when desired are readily detached from connection with the collar A. 95

From the foregoing description, taken in 100 connection with the drawings, the advantages of my improvement will readily appear. It

will be seen that the same is exceedingly simple in construction and very effective for its desired purpose. It can be conveniently carried by hand, is light, and can be made by any blacksmith at a very small cost.

Having thus described my invention, what I claim, and desire to secure by Letters Patent, is—

1. The combination, with the collar or band A, provided with apertures a' a' in its upper portion and a slot a in its lower portion, of the headed bolts or pins B, passed through said apertures a' a' and the slot a, whereby said bolts are disposed diagonally to each other, substantially as and for the purpose described.

2. The combination, with the collar or band A, provided with apertures a' a' in its upper face and a transverse slot a in its lower face, disposed centrally of the apertures a' a', of the headed pins or bolts B B, passed diagonally through the said apertures a' and slot a,

said bolts provided with pointed and enlarged flattened ends b' b', substantially as and for the purpose described.

3. The hereinbefore - described improvement in hitching-anchors, consisting of a band or collar A, provided with apertures a' a' in its upper part, a transverse slot a in its lower part, disposed centrally between the apertures a' a', and the pins or bolts B B, provided with heads b b, said pins passed through the said apertures a' a' and slot a, whereby said pins are disposed crosswise, said pins provided with enlarged and pointed ends b' b' and a ring or loop C, loosely held in the collar A, all arranged substantially as and for the purpose described.

In testimony whereof I affix my signature in presence of two witnesses.

WILLIAM W. MCKAY.
